(57) **CLAIM**

I claim the ornamental design for a portable lubrication unit, as shown and described.

DESCRIPTION

FIG. 1 is a perspective front view of the portable lubrication unit showing my new design, having a cover in an open position; and,

FIG. 2 is an alternative perspective front view thereof, having a removable lubricant supply container mounted on the portable lubrication unit for delivery of the lubricant there-through.

The broken lines showing various features in the drawings are for illustrative purposes only and those features form no part of the claimed design.
